MACHINE FOR MAKING FOUNDRY MOLDS

René Georges Marillier, Saint-Loup-sur-Semouse, France, assignor to "Etablissements A. Marillier," Saint-Loup-sur-Semouse, France, a society of France

Application December 18, 1951, Serial No. 262,214

Claims priority, application France
December 23, 1950

4 Claims. (Cl. 22—45)

1

The present invention relates to methods and machines for making foundry molds, these machines being of the kind which includes a table supporting a removable molding box filled with the molding material (sand), this table being pushed upwardly by a piston driven by a fluid under pressure toward a packing plate while the table undergoes relatively high frequency vibrations produced by a reciprocating hammer also driven by a fluid under pressure, this hammer being housed in a bore of said piston and striking, at least during the upward movement of the table, the under face thereof. After the molding material (sand) has been tightly packed in the cavities of the pattern, the table is lowered and removal of the mold from the pattern is facilitated by subjecting the table and the molding box to vibrations before this removal.

The object of the present invention is to provide improvements in such molding methods and apparatus.

For this purpose, according to an essential feature of my invention, the table is subjected, before contact of the molding sand with the packing plate, to one or several shocks of high intensity, produced at relatively low frequency, after which the high frequency vibration is applied by the hammer while the molding sand contained in the molding box is packed by the packing plate.

Other features of my invention will become apparent in the course of the following detailed description of some specific embodiments thereof with reference to the accompanying drawings, given merely by way of example, and in which:

Figs. 1 and 2 are diagrammatical views showing, respectively in elevation (partly in section) and in plan view, a machine for making foundry molds according to my invention.

Fig. 3 shows, on a larger scale and in longitudinal section on the line III—III of Fig. 4, the control means for moving the table of the machine upwardly and downwardly.

Fig. 4 is a bottom view of the power piston included in the means of Fig. 3.

Fig. 5 shows, in axial section, a modification of the means for temporarily connecting the lower part of the power piston with the hammer.

Figs. 6 and 7 are views similar to Fig. 4 showing the elements of the mechanism in different relative positions.

The machine as a whole is of conventional construction. In the example shown, it includes a support 1 carrying a fixed cylinder 2 in which is housed the mechanism for controlling table

3, which can be moved upwardly and downwardly. This mechanism will be fully described hereinafter. Support 1 also carries a column 4 the upper part of which carries, through an arm 5, a packing plate 6 adjustable in height. When the molding material (sand) in the molding box has been packed and table 3 has been lowered to make it possible to remove the molds, arm 5 may be pivoted, as well known, through 90° about a vertical spindle 7 into the position shown in dotted lines in Fig. 2, to facilitate access to table 3.

Frame 1 also carries, on one of its side walls, an oblique arm 8 the free end of which supports a valve system 9, controlled by means of a handle 10, for feeding a fluid (air) under pressure to move table 3 up and down.

A frame 57 is guided at every corner of table 3 by a vertical rod. This frame can be moved up and down by means of two vertical cylinders 11 in which pistons 12 are slidable. In order to obtain a vertical and perfectly plane movement of the frame, this frame is stiffened by plates 13. Through distributing valve 9 and orifices 56, fluid is fed to the chambers 55 at the lower part of cylinders 11, which causes the whole of pistons 12, frame 57 and the guiding rods to move vertically in the upward direction. Due to this vertical movement, the molding box 30 is moved away from the pattern plate placed on table 3, until the molded piece is cleared and can be removed from the table.

When the molding box is removed, fluid is caused, by means of distributing valve 9, to escape from chambers 55 and the whole structure is returned to its initial position. A new molding box is then placed on the pattern plate.

The molding box is filled with the molding material (sand) and the packing plate 6 is brought back, by rotation of arm 5 through 90°, above the table for the making of another mold.

All the parts above described are well known in the art and are not essential elements of the structure according to my invention, which is concerned with the means for controlling the upward and downward movement of the table and the operation of the hammer.

According to my invention, the molding box placed on table 3 and filled with sand or any other molding material is to be subjected to at least one shock before table 3 is moved upwardly toward plate 6 and is subjected to vibrations by the action of the hammer.

For this purpose, I provide in the fixed vertical cylinder 2 a piston made of two parts 14 and

2

3

15 coaxial and located one above the other. The upper piston element 14, upon which rests table 3, which is fixed thereto, includes, at the top thereof, a flange 16 adapted to rest on the upper edge of cylinder 2 and when flange 16 is resting on the top end of cylinder 2 and the lower piston 15 is in contact with the bottom of this cylinder, there is a space 17 (Fig. 3) between these piston elements. This space is in communication, through a conduit 18, with distributing valve 9 10 so as to be fed with a fluid under pressure, in particular compressed air, when said distribution valve is placed in the corresponding position.

When the lower piston element 15 is resting upon the bottom 19 of cylinder 2, the compressed air admitted into space 17 moves the upper piston element 14 and table 3 upwardly until the lower edge 20 of this last mentioned piston element comes to the level of the exhaust orifice or orifices 21 provided in the wall of cylinder 2 and opening to the atmosphere, so that this compressed air escapes suddenly into the atmosphere. As, in the meantime, the feed of compressed air to space 17 has been cut off, there is a sudden drop of the pressure under piston element 14, 25 which moves down suddenly under the effect of its weight until the flange 16 thereof strikes the upper edge of cylinder 2. A shock is thus imparted to the molding box carried by table 3, which thus produces an even distribution and 30 a settling of the sand in all the cavities of the pattern, more especially in the angular portions thereof.

If necessary, this operation is repeated as many times as wanted, by suitably operating distributing valve 9.

The upper piston element 14 which, as above described, serves to impart at least one shock to table 3 and the molding box placed thereon, prior to its upward movement for cooperation with packing plate 6, and the lower piston element 15, which has remained inactive up to this time, both cooperate in producing the successive upward and downward movements of the table, these two piston elements being provided with housings for the hammer which is to strike the under face of table 3 in a vibratory manner when the molding box is in contact with the packing plate 6.

For this purpose, I provide in the upper piston element 14 a bore 53 coaxial with said piston element outer wall and a cylindrical hammer 22 housed slidably in this bore. This hammer 22 extends downwardly beyond the lower end of piston element 14 and the lower end of this hammer 22 is also slidably engaged in a corresponding cylindrical bore 23.

During the operation of the upper piston element 14 in order to impart shocks to the molding frame placed upon table 3, as above described, hammer 22 should preferably not participate in the movements of this piston element 14 and should therefore be temporarily held stationary by the lower piston element, which does not move at this time. This may be done, as shown by Figs. 3, 6 and 7, by means of balls 24 movable in passages 25 including each two portions at right angles to each other. These passages 25 are distributed at regular intervals along the circumference of piston element 14. Each of them includes a portion making a small angle with the vertical axis of the piston and which opens into the upper edge thereof and a portion making a small angle with a horizontal plane and which opens into the cylindrical wall of said piston ele-

5 ment, opposite a circular groove 26 formed in hammer 22, when said hammer is in its lower position. When compressed air is introduced into space 17, this air automatically pushes back the balls present in passages 25 into groove 26, thus locking hammer 23 in its lowermost position, as shown by Fig. 3.

On the contrary, when the feed of compressed air to space 17 is cut off or when this space has been reduced to nothing by relative movement of the two piston elements 14 and 15, ball 25 automatically drops back under the effect of its weight into contact with an adjustable abutment 27 (Figs. 6 and 7). The hammer is then released and can be operated as it will be hereinafter explained.

This temporary holding of hammer 22 may also be obtained as shown by Fig. 5, where the bore 23a of the lower piston element 15 is of a diameter larger than that of the body of hammer 22. The lower end portion 28 of this hammer is made of a diameter fitting with that of said bore 23a. Thus, the hammer is held in lowered position by the pressure existing in space 17 and transmitted to the upper edge of said enlarged portion 28 through the space 29 between the wall of the piston bore and the wall of the body of hammer 22.

The lower piston element 15 rests freely upon the bottom 19 of cylinder 2 through circular rings 30 made of an elastic material, which act as shock absorbers. Piston element 15 is provided, at diametrically opposed points, with two longitudinal channels 31 which extend throughout the piston element. In each of these channels 31 there is mounted a check valve 32 carrying a small perforated disc 33. Each valve 32 is applied upon its seat 34 by the pressure of the compressed air admitted into space 17 and transmitted through the corresponding channel 31, so that this air cannot penetrate under the lower piston element 15.

On the contrary, when distributing valve 9 is adjusted to enable compressed air to penetrate through conduit 35 under the lower piston element, the feed of air into space 17 being of course cut off at this time, piston 15 is caused to move upwardly until it comes into contact with the upper piston element 14 (Fig. 6) so that space 17 no longer exists.

Valves 32 then open, which enables compressed air to pass through channels 31 into longitudinal passages 36 provided in piston element 14 at points diametrically opposed to each other. These passages 36 lead to holes 37 opening into the internal wall of said piston element 14 opposite a circular groove 38 provided in hammer 22 (Fig. 6). This groove 38 communicates through radial passages 39 with an axial conduit 40 provided in hammer 22, this conduit opening, at the lower end of this hammer into a recess 41 provided at the bottom of bore 23.

65 The compressed air admitted under the hammer pushes it upwardly from the position shown by Fig. 6 to that shown by Fig. 7 in which the hammer strikes the underface of table 3, this shock being transmitted to the molding box and its contents.

60 The inflow of air through holes 37 is cut off by the hammer itself when groove 38 moves beyond these holes. But the living force imparted to the hammer causes it to keep moving upwardly until it strikes table 3 (Fig. 7). The air located above the hammer can escape through

passage 42 into a chamber 42a formed at the lower part of table 3 and which communicates with the atmosphere through an adjustable check valve 42b, whereby it is possible to adjust the force with which the hammer strikes table 3.

When the hammer reaches its final position, a circular groove 43 provided therein and which communicates through radial passages 44 with the axial channel 40 of said hammer is placed in communication through holes 45 with longitudinal channels 46 which enable the compressed air present in chamber 41 under hammer 22 to escape to the outside. For this purpose, channels 46 communicate through holes 47 with an annular chamber 48 provided in the intermediate portion of piston element 14. This chamber is constantly in communication with exhaust holes 49 and 49a provided in the wall of cylinder 2 and connected together by longitudinal grooves formed in the inner face of this wall, whereby the compressed air can always escape to the atmosphere whatever be the position occupied by the lower end portion of piston element 14.

When, due to this exhaust, there is no longer a pressure above atmospheric pressure in chamber 41, the piston can move down under the effect of its weight, returning to the position shown by Fig. 6, where groove 38 is again opposite orifices 37. The cycle of operations above described is then repeated.

Figs. 6 and 7 show the hammer in its two end positions when the whole of piston elements 14 and 15 starts moving upwardly. The reciprocating movements of hammer 22 are maintained, as above stated, while the piston units 14-15 is moving upwardly until shoulder 50, formed at the lower part of piston element 14, comes into contact with a ring 51 which closes the upper part of cylinder 2 and also serves to guide piston element 14. Thus, the system formed by piston elements 14 and 15 cannot move beyond an upper limit position. As a rule, this system does not reach this position because packing plate 6 is adjusted at a height such that the molding box comes into contact with said plate before this system of pistons has reached this upper limit position.

When the machine operator judges that the sand contained in the molding box has been packed sufficiently between table 3 and plate 6 (this sand being subjected during this time to the vibrating action exerted by the hammer), he places valve 9 in the position which cuts off the feed of compressed air.

Once the sand has been packed, the air present under piston element 15 escapes through conduit 35 and distributing valve 9 which now occupies the position for which this conduit is in communication with the atmosphere. The lower piston element 15 and hammer 22 move down under the effect of their weight until element 15 comes to rest on the bottom 19 of cylinder 2, as shown by Fig. 3. The shock at the end of this downward movement is absorbed by elastic ring elements 30. The upper piston element also moves down until its top flange 16 comes to rest upon the upper edge of guiding ring 51.

Table 3 and the moulding box supported thereon move down together with piston element 15.

The operator then turns arm 5 and packing plate 6 into the position shown in dotted lines in Fig. 2, which clears the top of table 3. He then starts the well known vibrating device (not shown) generally located at 52 (Fig. 1) to facilitate the removing of the molded article 75

from the molding box. This operation is effected by placing valve 9 in the corresponding position, as briefly described above.

The machine is now ready for a new cycle of operations.

The movement of piston elements 14 and 15 toward each other is not necessarily obtained through pneumatic means but might be achieved through hydraulic, mechanical or electrical means.

Piston elements might be disposed one about the other, one of them serving to produce the shocks as done by piston element 14 in the construction above described and the other serving to drive the table toward the packing plate, in combination with the vibrating shocks produced by the hammer. The two piston elements would then be driven through pneumatic, hydraulic or mechanical means.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

30 What I claim is:

1. A machine for making foundry molds which comprises, in combination, a fixed support, a vertical cylinder carried by said support, a packing plate carried at a fixed height by said support, a piston element movable in said cylinder, a table carried by said piston element at the top thereof, a second piston element movable in said cylinder, said two piston elements being arranged to leave between them, when both of them are in their respective lowermost positions, a closed space so disposed that a pressure increase therein urges the first mentioned piston element upwardly and the second mentioned piston element downwardly, means for feeding a fluid under pressure into said space, said cylinder being provided with exhaust orifices located so as to communicate with said space when it is expanded to a predetermined volume by said fluid under pressure raising said first mentioned piston element, said second piston forming a closed chamber between itself and the bottom of said cylinder, means for feeding a fluid under pressure into said chamber said space being so arranged as to be reduced to zero when said second mentioned piston element is moved upwardly by the action of said last mentioned fluid under pressure fed to said chamber, whereby the feed of said last mentioned fluid under pressure moves both of said piston elements upwardly, said piston elements being provided with longitudinal bores in line with each other, and a hammer slidably in said bores, said piston elements being provided respectively with inter-communicating longitudinal channels arranged to communicate with said chamber, the portion of said hammer housed in the first mentioned piston element being provided with an annular groove, this last mentioned piston element being provided with a hole in communication with said longitudinal channels of said piston element and opening into said last mentioned groove, said hammer being provided with an axial bore in communication at the top with said last mentioned groove and opening at the bottom into the bottom face of said hammer,

said hammer being provided with another groove located under the last mentioned one and in communication with said axial bore, and said cylinder and said first piston being provided with exhaust passages for connecting with the atmosphere the last mentioned groove in the hammer when said hammer has moved a given distance upwardly under the effect of the fluid under pressure fed through said channels and said bore.

2. A machine according to claim 1 in which the lower part of the cylindrical wall of said hammer is provided with a circular groove, said second mentioned piston element being provided with passages each of which opens at one end 15 into said space between the two piston elements and at the other end into the cylindrical wall of the bore in said second mentioned piston element opposite said groove in said hammer, and balls in said passages adapted to engage in said 20 groove for holding the hammer with respect to the second mentioned piston element.

3. A machine according to claim 1 in which the lower end of said hammer is of a diameter larger than the remainder thereof, the cylinder 25

drical bore provided in the second mentioned piston element being of a diameter fitting with that of said lower end of the hammer and the top of the last mentioned cylindrical bore opening into said space between the two piston elements, whereby said hammer is urged downwardly by the pressure existing in said space when fluid under pressure is fed thereto.

4. A machine according to claim 1 including, in the longitudinal channel provided in the second piston element, a check valve opening upwardly for connecting said chamber with said channels.
